UNITED STATES PATENT OFFICE.

GEORGE HOLT FRASER, OF NEW YORK, N. Y.

SCREENING APPARATUS.

1,202,378.

Specification of Letters Patent. Patented Oct. 24, 1916.

Application filed December 4, 1915. Serial No. 64,995.

To all whom it may concern:

Be it known that I, GEORGE HOLT FRASER, a citizen of the United States of America, residing in the borough of Brooklyn, county 5 of Kings, city and State of New York, have invented certain new and useful Improvements in Screening Apparatus, of which the following is a specification.

This invention relates to apparatus for 10 screening coarse from fine material, and aims to provide certain improvements therein especially applicable to inclined screens.

To this end the invention provides certain improvements in construction which 15 will be hereinafter more fully set forth with reference to the accompanying drawings, in which—

Figure 1 is a side elevation of the preferred form of my improved screen; Fig. 2 20 is a rear elevation thereof partly broken away to show sections on different planes; Fig. 3 is a vertical cross-section cut on the line 3—3 in Fig. 2; Fig. 4 is a longitudinal section cut on the line 4—4 in Fig. 3; Fig. 5 25 is a similar section cut on the line 5—5 in Fig. 3; and Figs. 6 and 7 are enlarged fragmentary views showing a corner of one of the screen members. Figs. 8 and 9 are enlarged detail views of the knocker, showing 30 the under plate preferably used for limiting excessive lost motion of the hammer bars.

Referring to the drawings, A is the casing as a whole, B are the screen members therein, C is the feed hopper, D is the coarse outlet, E is the fine outlet, F is the drive pulley, and G are the vibrators.

The casing is a tubular member hinged at 40 a to feet b, and adjustably connected at c to legs d so that it can be tilted to vary the inclination of the screen. It is preferably made entirely of metal, and in its preferred form consists of cast iron side pieces e which are united by braces f, g, h and i, the top of the casing being inclosed by removable 45 hinged doors j, and the back by a hinged bottom k, the front being closed by a vertically sliding door l, and the bottom being open for the outlets D and E. The upper part of the casing is formed with front and 50 rear doors m which inclose the distributing conveyer, and with a reversible top plate n, which, with the hopper C, can be removed

and placed so as to locate the hopper at either side of the machine.

The side pieces e are preferably formed 55 with a lower body portion o and an upper head portion p with an intermediate flange q, and with bearing supports r, all in one integral casting. The body portion o has a lower edge s inclined downwardly relative 60 to its upper edge, and against which the back or bottom closes. The upper edge has a flange t against which the top covers j set to close the top of the body, which flange has notches or recesses u u to receive corresponding projections v v on the covers, so that the latter will not slip down in case either end is raised.

On its inner face each side is provided with a shoulder or flange H against which 70 the screen member rests, and by which the latter is arrested in its upward movement, which shoulder is preferably a part of the casting.

Internal flanges w are provided on the 75 head p for supporting cross bars x, which, with a plate y resting on them constitute the trough for the distributing conveyer I. Adjustable or tilting feed plates J are fastened on the front and rear sides of this trough, 80 and are tilted to the angle necessary to cause the conveyer to feed material from the trough over the edge of the plates in an approximately uniform stream from end to end, according to which direction the conveyer is driven. The feed plates have out-bent ears z which are engaged by adjusting bolts a' for adjusting the angularity of the plates.

The conveyer has a driving shaft K, on 90 one end of which is mounted the drive pulley F, and on the other end of which is a crank b' or other provision for operating the agitating mechanism for the screen.

The hopper C has flanges c' depending at 95 each side of the conveyer to prevent material from shooting upwardly before it falls into the trough, and it has a transverse flange d' on which the top n is fastened.

Beneath the conveyer is a deflector plate 100 L extending from the back downwardly over the screen member, and opposite this is a reverse inclined feed plate M extending from the front rearwardly, beneath the

lower edge of which plate is a feed aperture N through which the material may pass to the screen. Above these plates is a deflecting flange O which prevents the plates 5 from rising, and deflects toward the center any material falling close to the wall. Stops e' are provided for limiting the downward movement of these plates. Each plate can be slid upwardly and outwardly through 10 the adjacent door m .

The screen member B is a vibrating spring-mounted screen consisting of a frame composed of side angles or bars j' connected by transverse angles or bars g', h' , and 15 carrying intermediate channels or bars l' on which are mounted the one or more sections of removable screen frames P .

The screen member is hinged or removably and loosely connected within the casing, so that it can be folded downwardly to permit access to the screen. It is flexibly mounted, preferably by being carried by springs j', j'' which are adjustable on rods k', k'' , which springs hold the frame toward the shoulder or stop H and draw it forcibly against this stop after it has been depressed, thus giving it an upward jar tending to lift the material from the meshes of the screen. For greater sensitiveness and 30 elasticity, the screen is also preferably supported by springs l', l'' acting in direction at right angles to the springs j' , these springs being carried by rods m' which are respectively supported detachably and adjustably from the cross bars g and h of the casing, and constitute flexible hinges.

The removable screen frames P are preferably all metal, and are shown as consisting of cross angle bars n' having holes 40 o' , and longitudinal bars p' adjustably or rotatively mounted in these holes, and screen cloth q' , clamped between these bars and resting on the inwardly projecting flanges r' of the cross bars. The ends of the flatings 45 of the cross bars are bent outwardly at s' and are recessed or perforated at t' , and the longitudinal bars are half-rounds having transverse holes u' through which a cotter or other holding means v' may be passed 50 so as to traverse one of the holes u' and prevent rotation of the longitudinal rods. At suitable places the longitudinal rods are provided with transverse holes by means of 55 which they may be clamped together against the screen cloth by screws w' .

The vibrating mechanism preferably consists of oscillating knockers which strike on the top of the screen member. As shown, these consist of spring arms z' loosely 60 mounted on cross shafts y' and held by clamps z'' which are bolted or keyed to the shafts to oscillate with them, and which loosely engage and guide the knockers so that they will strike the screen member 65 properly, but may be passive relatively to

the shaft during a part of its oscillation. The shafts are keyed to rocker arms a'' connected together by a connecting rod b'' , and to the crank b' by a pitman rod c'' so that the arms will be oscillated with the 70 revolution of the crank. The clamps z' have half-round portions d'' fitting the shaft at each side of the spring, and an intermediate chamber e'' the wall of which loosely embraces the spring, and a bearing or striking portion f'' for engaging the spring remote from the shaft to transmit part of the 75 oscillation of the shaft to the spring, and depending guiding fingers g'' embracing the sides of the spring to guide it in its oscillations. The lower side of each clamp is open so that by releasing the bolt h'' holding it to the shaft, it may be lifted off, thus 80 freeing the spring. The spring has a central bend portion embracing the shaft, but so sufficiently yielding to permit it to be sprung off from the shaft, so that any knocker can be removed or replaced without necessitating removal of the shaft. The springs are 85 preferably made of untempered tool steel, so that they can be bent to give the proper stroke in knocking, and may have sufficient lost motion in the clamps to permit them to oscillate independently sufficiently to give a quick stroke during the time that the 90 crank is passing the dead center and the clamps are reversing.

The bearings for the shafts are preferably ball bearings Q , insuring alignment independently of any skewing of the frame, 10 and permitting sufficient rocking of any shaft to enable it to be counted sufficiently to remove it without taking apart the frame when the shaft has been slid endwise in the bearing enough to free it from the opposite bearing. These bearings are made by casting or forming on the side pieces n the brackets r which have a cylindrical bore t'' in which fits a spherical portion j'' on the bearing, so that the latter can rock in any 100 direction. Each bearing is formed with an oil cup k'' having projecting ears l'' which are cottered or otherwise fastened to a rib m'' on the bracket r , thus preventing the bearing from falling out. Oil covers n'' 110 are likewise fastened to these ears.

In operation, with the construction shown the hopper C is placed at whichever side of the machine it is desired to feed the material, and the conveyor I is revolved in whichever direction is necessary to push the material from the hopper toward the other end of the machine. The bottom y of the trough is shorter than the length of the conveyor, and is moved from one end to the other of the trough in order to leave the bottom outlet opening at the end of the trough remote from the feed hopper, so that any material not thrust over the feed plates may fall through this end. The front and 130

- rear feed plates are tilted until the material flows across one or the other in a uniform film from end to end. When material is fed to the hopper, the conveyer will then 5 distribute it evenly onto either the rear feed plate L or the front feed plate M, according to the direction of rotation of the conveyer. If the feed falls onto the screen plate M it will flow backwardly down the latter and 10 be discharged onto the other plate L, down which it will flow onto the screen. The feed plate L rests on the screen member and is slightly vibrated thereby, thus insuring free flow of the material down this plate. 15 These adjustments having been made, the inclination of the body and screen member will be varied, until the desired fineness of screening is effected, by raising or lowering the back end of the separator by placing the bolt *c* in any of the holes *p* corresponding to the inclination desired. This will oscillate the body around the bolt *a*, and in this manner the adjustment can be varied from a normal inclination of 45 degrees as much 25 as desired. Vibration of the screen will then be adjusted by tightening or loosening its supporting springs *j*' and *l*', and by bending the spring knockers *x*' until they hit the requisite blow. The screen supports should 30 be adjusted to delicately poised the screen so that the knockers will easily vibrate it, and so that its upward movements will be arrested by the shoulder *H*. When these adjustments have been properly made the material will flow down the screen surface in a thin film, and the agitation will prevent clogging of the interstices, and will facilitate the flow of the coarse particles down over the screen and discharge of the fines 35 through the screen. The fines falling through the screen will flow down the steeper inclined bottom *k* to the fine outlet E, the greater inclination of this bottom insuring a gravity flow even when the adjustment is such that the screen member is too flat for a gravity flow without vibration. 40 Operation of the distributing conveyer may be observed through either the front or rear doors, and the knockers and screen action may be observed through the top doors *j*. The screen frames may be removed by sliding them backwardly out through the back door *q*' or forwardly through the front door *l* after their clamping screws *r*' 45 and clamping plates *s*' have been removed, or access to their rear may be had by turning down the bottom door *k*, or they may be released from their spring supports and turned down on the bottom door and taken 50 out and replaced while in this position. If the material being screened is damp, it may be ventilated or dried by tilting up the lower edge of one top door *j* and opening the back door *q*', thus permitting a current 55 of air to flow backwardly through the cas- ing downwardly through the screen and outwardly at rear. A piece of screen *t*' may be placed inside of the door *q*' to prevent dust floating out during such ventilation. 60 For dry screening the apparatus may be used as shown, and for wet screening it may be immersed in water. It will be seen that the legs can be folded against the body, and that the apparatus can be easily taken apart for packing in knock-down shape, and assembled for use; also that the driving pulley and agitating mechanism can be placed at either side by simply removing the shafts and their connections, and reversing their positions before again assembling them. 65 The screen frames can be made entirely of metal, and the cloth can easily be clamped between the longitudinal bars and then properly stretched by turning the bars, and retained in position by fastening the bars in the cross pieces. With the proper width of cloth its selvage will assist in preventing it from slipping between the bars. The cross pieces in conjunction with the bars and their cotters, are in the nature of adjustable ratchet connections, for which any ratchet or other suitable adjusting means may be substituted. The wings of the channel irons 70 engage the longitudinal members of each screen and prevent inward springing between the cross pieces. 75 It will be seen that this invention provides means which can be readily and advantageously availed of, and it will be understood that the invention is not limited to the particular details of arrangement, construction or combination set forth as constituting its preferred form, since the improvements can be employed in whole or in part according to such modifications or adaptations as the judgment of those skilled in the art may dictate, without departing from the spirit of the invention. 80 In lieu of the rigid flange as a stop, stop nuts may be adjustably screwed on the spring rods as shown. 85 While I have herein shown and described the feeder and distributor set forth the same is not claimed in this application, being the subject matter of claims in my application Serial No. 454,604, filed September 24, 1908. 90 I claim as my invention:— 95 1. In screening apparatus, an inclosed inclined screen in combination with a casing in which it is inclosed, and downwardly acting jarring means above said screen for vibrating it, said casing having a detachably carried bottom wall independent of and of greater inclination than the screen. 100 2. An inclined vibrating screen, in combination with means for jarring said screen, and a casing inclosing it having a hinged bottom wall hinged to its lower part. 105 110 115 120 125 130

3. An inclosed inclined screen, in combination with an adjustable casing inclosing it, means for adjusting the angularity of said casing, adjustable means yieldingly supporting the screen in said casing, stops or surfaces for arresting upward movement of said screen in said casing, and means for downwardly jarring said screen.
4. A casing for a screen consisting of side plates having an inclined top edge, a bottom edge of greater inclination than said top edge, an internal shoulder, bearing brackets, and deflector flanges, in combination with a screen member within said casing, springs yieldingly drawing said screen member against said shoulder, feed plates seated on said flanges, a distributor above said feed plates, and vibrating mechanism carried by said bearing brackets.
5. In screens, a screen member consisting of an inclined frame, springs reacting against and supporting said frame in an upwardly and forwardly direction, and springs reacting against and supporting said frame transversely of said first mentioned springs and in an upwardly and rearwardly direction.
6. In screening devices, a screen member comprising a screen cloth in combination with adjustable longitudinal members between which the edges of said cloth are clamped, cross members movably holding said longitudinal members apart, and means for adjusting said longitudinal members relatively to said cross members to tighten said cloth laterally of the screen member.
7. In vibrating screens, a knocker consisting of a passive striking member and an oscillating part for moving it toward and from the screen, said part and member having a lost motion connection.
8. In a separator, the combination with an inclosed screen of independent loosely mounted striking members, above said screen for acting downwardly against it to jar it, oscillating members mounted on fixed axes above said screen and acting on said striking members to cause them to percussively jar said screen and revolving means for swinging said oscillating members.
9. In a separator, the combination with an inclined screen, of swinging strikers hinged on fixed axes above said screen and acting percussively downwardly toward the latter to jar it, means loosely engaging said strikers for lifting them, and a revolving part operating said lifting means.
10. In a separator, the combination with an inclined screen, of independent loosely mounted members or strikers above said screen for jarring it, oscillating means swinging on a fixed axis above said screen for operating said strikers, and a revolving part operating said oscillating means.
11. In a separator, the combination with an inclined screen of impact members or strikers acting percussively downwardly on said screen to jar it, swinging or oscillating parts pivoted on a fixed axis above said screen and operating said strikers, means for varying the stroke of said strikers, and a revolving part operating said oscillating means.
12. In a separator, the combination with an inclined screen, of a spring-impelled impact member above and acting percussively on said screen to jar it, a swinging member oscillating on a fixed axis above said screen and acting on said impact member or striker, and a revolving part for operating said swinging member.
13. In a separator, the combination with an inclined screen comprising wire mesh screen cloth, in combination with a frame therefor comprising longitudinal and cross members to which said cloth is attached, said cross members movably holding said longitudinal members adjustably relatively to said cross members, and means for positively adjusting said longitudinal members for adjusting the tension of the said screen cloth.
14. In a separator, the combination with a screen comprising woven mesh screen cloth, of a screen frame comprising cross members to which said cloth is attached, and longitudinal members to which said cloth is attached, one of said longitudinal members movably connected to said cross members to move about a predetermined axis relative thereto, and means for moving said movable member to adjust the tension of said cloth.
15. In a separator, the combination with a removable inclined screen comprising a screen member having a downwardly extending part or member at its edges of a frame or casing inclosing said screen and having side walls, angles or bars mounted against the side walls of said frame or casing and sustaining said screen, and having upwardly extending parts or flanges inwardly of said downwardly extending parts or members of said screen.
16. In a separator, a removable inclined screen comprising a screen member having a downwardly extending part or flange at its edge, a casing in which said member is resiliently mounted, and an angle or bar mounted in said casing beneath the edge of said screen and sustaining the latter, and having an upwardly extending flange or part at the inner side of and engaging said flange of said screen for sustaining the latter.
17. In a separator, a screen comprising a screen member and a bar or angle on which said screen member is mounted having a downwardly extending part or flange, a bar or member mounted transversely of said casing beneath said screen member and

- ing an upwardly extending wall or flange beneath and engaging the inner side of said flange and sustaining said screen.
18. In a separator, a removable inclined screen comprising a wire mesh screen clothing and a frame on which said clothing is stretched, comprising an oblong frame having longitudinal side members and transverse end members connecting said longitudinal members and comprising a bar or angle having a face on which said screen is mounted and a downwardly extending flange projecting from said face, and a casing inclosing said screen and having a bar or member beneath and sustaining said screen under and engaging said downwardly extending flange.
19. In a separator, the combination with a removable inclined screen, of a casing having side walls inclosing said screen, bars or angles mounted against said side walls and sustaining said screen and having an upwardly extending flange beneath said screen affording a groove or duct for material leaking past the edge of said screen.
20. In a separator, the combination with a removable inclined screen comprising a rectangular screen frame and wire mesh clothing mounted thereon, of a casing inclosing said screen, and bars or angles mounted at the inner side walls of said casing below said screen and having upwardly extending flanges inwardly of the sides of said frame and sustaining the latter.
21. In a separator, a plurality of removable inclined screens, in combination with a casing in which said screens are mounted, and means supporting adjacent edges of two of said screens comprising a bar or groove beneath and sustaining said screens, having upwardly extending flanges affording a downwardly extending groove under the adjacent edges of said screens.
22. In a separator, a plurality of removable inclined screens comprising a screen clothing and a rectangular frame on which said clothing is mounted, a frame or casing on which said screens are mounted, and bars or grooves supporting said screens having upwardly extending flanges projecting within said screen frames and engaging the inner sides thereof for sustaining said screens.
23. In a separator, the combination with a removable inclined screen comprising a rectangular screen frame and screen clothing mounted thereon, of a casing inclosing said screen and having side walls, a transverse bar mounted in said casing between said side walls and removably sustaining said screen, mounted under the top of said screen and separably sustaining the latter.
24. In a separator, the combination with a screen comprising a rectangular screen frame and a screen clothing mounted there-
- on, of a casing inclosing said screen, and a transverse bar crossing between the side walls of said casing below the lower edge of said screen and resiliently supporting the latter.
25. In a separator, a removable inclined screen in combination with a casing inclosing said screen, bars extending transversely of said casing below the upper and lower edges of said screen, and downwardly extending bars below and sustaining said screen mounted at their extremities on said transverse bars.
26. In a separator, a resilient removable inclined screen comprising an oblong rectangular metallic screen frame, wire mesh clothing mounted thereon, and means for adjusting the longitudinal members of said screen frame to stretch said clothing.
27. In a separator, a resilient inclined screen comprising a rectangular screen frame and wire mesh clothing stretched thereon, said frame comprising end angles or bars having a flange or part beneath and in the plane of said clothing, and a flange or part projecting downwardly at right angles to said clothing, and means for stretching said clothing on said frame.
28. In a separator, the combination with a resilient inclined screen, of a casing inclosing said screen, means resiliently supporting said screen in said casing at its upper edge, and impactive jarring means acting on said screen intermediate of its upper and lower edges.
29. In a separator, a plurality of removable inclined screens, a casing inclosing said parts, means resiliently sustaining said screens in said casing, and impactive jarring means opposite adjacent edges of two of said screens.
30. In a separator, the combination with a plurality of inclined screens of a casing in which said screens are mounted, means resiliently supporting said screens, means arresting upward movement of said screens, and jarring means above said screens.
31. In a separator, a plurality of inclined resilient screens, a casing inclosing said screens, angles at the side walls of said casing sustaining the outer edges of said screens respectively, and a groove or bar intermediate of the side walls of said screens and having upwardly extending flanges sustaining the adjacent edges of two of said screens, and jarring mechanism for said screens.
32. In a separator, a resilient inclined screen comprising a rectangular metallic frame and a wire mesh screen clothing mounted thereon, in combination with a casing inclosing said screen and comprising angles or bars mounted at the side walls of said casing and sustaining the side edges of

said metallic frame, and impactive jarring mechanism above said screen for percussively jarring the latter intermediate of said edges.

5. 33. In a separator, a resilient inclined removable screen comprising a rectangular metallic frame and wire mesh screen clothed stretched thereto, in combination with a casing in which said screen is mounted comprising a transverse metallic bar under and sustaining the upper edge of said screen,

means sustaining said screen downwardly from said bar, and percussive jarring mechanism for said screen above the latter.

In witness whereof, I have hereunto signed my name in the presence of two subscribing witnesses.

GEORGE HOLT FRASER.
